UNITED STATES PATENT OFFICE

2,609,204

RADIO AND/OR TELEVISION GAME APPARATUS

Herbert H. Wixson, North Hollywood, Calif.

Application May 21, 1949, Serial No. 94,619

2 Claims. (Cl. 273—139)

1 This invention relates to a radio and/or television game and deals more particularly with a chart-type of game board apparatus for use in the preparation, production and presentation of radio-television programs of the quiz, puzzle, contest or game type of program.

An object of the present invention is to provide a chart board for the above-indicated purposes, whereby a contestant, whether in the studio audience or at home, may participate in a program and benefit by receiving a prize or prizes according to a designated selection of one of a plurality of plaques arranged on said board, said board being of such nature that the elements of surprise, interest and the attention of the listeners are present.

Another object of the invention is to provide a chart board as indicated in which the plaques are so arranged that each may be selected by number, said plaques carrying and concealing a "point value" or prize-indicating element that becomes visible only upon removal of a plaque from the board.

A further object of the invention is to provide, in a chart board, a complement of plaques that carries the fifty-two cards of a conventional playing card deck, whereby a great variety of point values may be achieved.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes embodiments of the present invention, which are given by way of illustration or example only.

In the drawings, like reference characters designate similar parts in the several views.

Fig. 1 is a face view of a game board embodying a preferred form of the present invention.

Fig. 2 is a similar view of an alternate form of game board.

Fig. 3 is an enlarged fragmentary sectional view, as taken on line 3—3 of Fig. 1.

Fig. 4 is an inner face view of one of the plaques on the board of Fig. 1.

Fig. 5 is a fragmentary sectional view, as taken on line 5—5 of Fig. 1.

Fig. 6 is an inner face view of one of the plaques on the board of Fig. 2.

2 The game board that is illustrated in both Figs. 1 and 2 comprises a background board 10 that is of the bulletin type, is covered with a felted material, and is provided with a uniformly spaced series of horizontal grooves 11. Said grooves, in a conventional manner, are adapted to receive and hold in place suitable letters, numerals, symbols, etc. The upper portion 12 of the board 10, in this instance, is shown as bearing radio or television station call letters 13 and a word or words 14 indicative of the name or purpose of the present game. The letters and words 13 and 14 are comprised of elements that are held in the grooves 11 of area 12 and are replaceable, as can be understood. A lower area 15 is also provided on the board for additional wording, such as sponsors and sales slogans, etc.

The intermediate or playing area 16 of the board, is the same for both forms shown. In each case, across the upper end of area 16, there is arranged a set of numerals 17 reading from "0" through "9", and vertically along the left side of said latter area is arranged a similar set of numerals 18 and also reading from "0" through "9". The "0" is common to both sets of numerals. Suitable lines or stripes 19 may be provided to define area 16 and also set apart numerals 17 and 18 from the remainder of said area.

In the form of Fig. 1, the set or complement of plaques 20 are fifty-two in number, and the same are symmetrically arranged in area 16 in transverse and vertical rows coordinated with numerals 7 and 8. Since area 16 is adapted to accommodate eighty-one plaques in rows of nine each, the fifty-two plaques used are preferably arranged to provide an open central area 21 within the playing area 16.

Each plaque 20 is shown as a sheet metal rectangular element 22 that has opposite flanges 23 adapted to be received in grooves 11. Preferably, elements 22 are slightly arched so they stand away from the face of board 10, enabling the unflanged edges thereof to be grasped for ready removal of a plaque from the board. The inner side of element 22 is provided with a playing card 24, such as indicated in Fig. 4, said card being either cemented to the element or stapled thereto.

Fig. 2 shows a full complement of eighty-one plaques, each of which is similar to the plaque above described, except that playing card 24 is replaced by a card 25 which bears a given point value and/or a question or other indicia thereon.

The central area 21 may bear letters, numerals or symbols, or, as shown, a placard or sign

26 may substantially occupy said area and be held in place by corner clips 27 which enter grooves 11 of the board. Said area 21 or placard 26 may bear a sponsor's name or other suitable indicia.

Employing the board of Fig. 1, a contestant, in the studio audience or at home, will select a plaque by number. Said plaque will then be removed and the point value thereof will be shown—two points to a deuce, three for a troy, etc. Face or picture cards will have a value of ten, and aces a value of fifteen. The selection of the card may be preceded by the posing and answering of a question. Another or the same contestant may then continue answering questions and indicating a selection of plaque until either the plaques are all removed or the program time runs out. The awarding of prizes may be on the basis of individual point values of each plaque, or on an accumulation of point values, as desired.

The game or contest is conducted in a somewhat similar manner with the board of Fig. 2. In this case, however, the plaque may carry the question and the point value therefor as shown in Fig. 6.

Since the plaques are readily removed and as easily replaced, the present board is admirably suited not only to secretive arrangement of the various plaques and the cards they bear, but different complements of plaques may be associated with a single board so that the game or contest for a particular program may be quickly set up. No rehearsal is required and the game is so flexible that questions, puzzles, spelling bees, code contests, checker and chess games and other games can each quickly be arranged, even for programs that immediately follow each other.

It will be evident that the present game apparatus greatly facilitates the contest type of game now so prevalent in radio and television programs.

While the invention that has been illustrated and described is now regarded as the preferred embodiment, the constructions are, of course, subject to modifications without departing from the spirit and scope of the invention. It is, therefore, not desired to restrict the invention to the particular forms of construction illustrated and described, but to cover all modifications that may fall within the scope of the appended claims.

Having thus described the invention, what I claim and desire to secure by Letters Patent is:

1. Game apparatus of the character described, comprising a game board having a series of grooves in the outer face thereof, a horizontal and a vertical row of numerals on the face of said game board, each numeral of one row combining with any of the numerals of the other row to constitute a number comprising two of said numerals and each such number designating a space on the face of the game board, and a removable plaque occupying each of said spaces and embodying projections that enter the mentioned grooves, each plaque bearing indicia on the face thereof that is directed toward the face of the game board.

2. Game apparatus of the character described, comprising a game board having a series of grooves in the outer face thereof, a horizontal and a vertical row of numerals on the face of said game board, each numeral of one row combining with any of the numerals of the other row to constitute a number comprising two of said numerals and each such number designating a space on the face of the game board, and a removable plaque occupying each of said spaces and embodying projections that enter the mentioned grooves, each plaque having a conventional playing card secured to the face thereof that is directed toward the face of the game board.

HERBERT H. WIXSON.
